(57) **CLAIM**

The ornamental design for a bottle cooler and warmer as shown and described.

DESCRIPTION

FIG. 1 is a side perspective view of a bottle cooler and warmer and associated bottle according to an embodiment of the present disclosure.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is a side perspective view of the bottle cooler and warmer without the associated bottle according to an embodiment of the present disclosure.

FIG. 9 is a top plan view thereof.

FIG. 10 is a front elevation view of the associated bottle without the bottle cooler and warmer according to an embodiment of the present disclosure; and,

FIG. 11 is a bottom plan view thereof.

The shade lines in the Figures show contour and not surface ornamentation. The broken lines in the Figures show portions of the bottle cooler and warmer that form no part of the claimed design.
